UNITED STATES PATENT OFFICE

2,442,390

APPARATUS FOR CLEARING MINE FIELDS

Allison R. Williams, Yazoo City, Miss.

Application March 10, 1944, Serial No. 525,962

1 Claim. (Cl. 89—1)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to mine field clearing devices and particularly to such devices carried by the track plates or tread plates of a standard military tank or other heavy vehicle of the track laying type. The invention also contemplates the use of heavy kinetic energy absorbing masses constructed in accordance with the teachings of my application Serial Number 519,142, filed the 21st day of January, 1944, which has matured into Patent No. 2,425,018.

In that application, I have disclosed the use of impact elements capable of traversing a mined area and exploding any mines planted therein by impact and sustained pressure. According to the principles disclosed in that application, it is proposed to reduce substantially the forces applied to the supporting and conveying structure for the impact elements by so designing those elements relatively to area exposed to the blast of an exploding mine and the mass of the exploder elements that only a small fraction of the kinetic energy from the blast is imparted to the mass of the element itself. Thus only a moderate velocity is imparted to the element and hence a limited amount of impact to the supporting structure. The proportioning of the parts according to the teachings of that application can be expressed mathematically by the formula:

$$F = \frac{KA}{W_s S}$$

where

F =mean retarding force required to bring the element to rest in distance S ,

W_s =exploder weight,

S =travel of exploder before coming to rest,

K =a constant for a reasonable range of the variables A and W_s ,

A =effective area exposed to blast.

It is apparent from this empirical formula that the retarding force necessary to bring the exploder to rest varies directly as the area of the exploder subjected to the mine and inversely as the weight of the exploder and the length of its travel before coming to rest. Consequently, the value of F may be controlled to obtain a desired value for the velocity imparted to the exploder by suitable proportioning of the quantities in the above formula. Tests have indicated that the

2

constant K is not the same for every area and every weight, but increases somewhat as the area increases and as the weight decreases.

The object of the present invention is to provide exploders which may be attached directly to the track blocks or tread plates of a military tank so that the tank may itself act as a mine field clearer. It is also proposed to so design and proportion these exploders that they may absorb a substantial portion of the kinetic energy from the blast of an exploding mine, only a small fraction of the energy liberated from the blast being imparted to the exploder as kinetic energy, so that only a moderate force is applied to the tread and its conveying means. In this way, use may be made of a standard vehicle requiring only minor changes, which could be accomplished in the field.

By the use of exploders attached directly to the tread plates, as by welding, substantially the only changes required in the standard structure will be the use of plates with stronger supporting pins of the tread, of the bogie wheels which have a thicker rim and an extra plate of metal in the bottom of the tank body so as to protect the occupants from the nearness of the blast and the added pressure which will be applied to the tank body as a result of the use of exploders carried by the tread.

The invention will be more fully understood from a reading of the following specification in connection with the accompanying drawings in which:

Figure 1 is a side view of a portion of a so-called "medium" tank showing a section of the tread with mine exploders attached to it;

Figure 2 is a front view of one form of exploder shoe embodying my invention as it appears attached to the tread plate of a tank;

Figure 3 is a side view of the shoe of Figure 2;

Figure 4 is a bottom plan view of the exploder shoe shown in Figure 2;

Figure 5 is a bottom plan view of a companion exploder shoe adapted for use in conjunction with that of Figures 2 and 3;

Figure 6 is a front view of the exploder shoe shown in Figure 5; and

Figure 7 is a developed view of the pattern made by the exploder shoe tread as it passes over a mine field, indicating how the exploder shoe ends cover the area so as to strike all areas within which anti-tank mines of known size could be planted.

Referring to Figure 1 of the drawings, this figure shows enough of the tank to illustrate the principle of the invention, other parts being bro-

ken away. In this figure, reference character 11 designates the tank body having, in accordance with usual practice, an endless tread on each lateral side, the portion of one only of these treads being shown in the drawing. The tread as shown is made up of tread plates or blocks 15 connected together by links 14 running about bogie wheels 12 supported on axles 13. The treads are, of course, driven by an internal combustion engine disposed within the tank body and are subject to control in any conventional manner through main drive sprockets. Since the driving mechanism and its control is not a part of the invention, further description will be unnecessary.

The tread plates 15 carry at each end two pins 21 (Fig. 3), and the pins of adjacent plates are joined by the links 14 and clamping devices of known construction permitting removal and replacement of any tread plates at will. In accordance with the present invention, each of the tread plates has welded thereto a heavy mass exploder element carrying either two or three mine exploding projections or shoes. As shown in Figure 2 the tread plate 15 has welded thereto as indicated at 22 an exploder 16 carrying two projections 18 having exposed ends of small cross section tapering and enlarging into the body of the mass which at its base has a configuration and dimensions similar to the face of the tread plates 15. The base of the exploder extends laterally beyond the tread plates in such a way as to form shoulders 23 to protect the tread pins 21 from the blast of an exploding mine. The streamlining of this base is such that there are no exposed corners or projections to present a vulnerable section to the blast of an exploding mine. The mass of the exploder with its projection is, of course, designed according to the equation indicated above so as to reduce to a safe value the amount of force which is applied to the tread and its supporting means.

In order to provide a pattern of contact areas between the ground and the exploder feet or foot prints, the exploder elements 16 having two projections are alternated with similar elements 17 having three projections. The exploder 17 has a central projection 18 similar to the projections 18 carried by the exploder 16. However, adjacent to the two ends of each exploder 17 are projections 19 thinner than the projections 18, 18' and also streamlined and designed to present the minimum of exposed surface to the blast of an exploding mine beneath the end of the projection. The ground contacting face of the exploder 17 is indicated in Figure 5 and a side view of the same construction appears in Figure 6.

The developed pattern or foot print produced on the ground as the tank travels along is indicated in Figure 7, where it will be seen that not only is there a symmetry of the points of support for the tread and its superimposed weight, but also that the projections 18, 18' and 19 are so positioned relative to each other as to explode any anti-tank mine which may be buried in the area of the tank tread. The dotted circles 24 represent mines of the minimum size likely to be encountered.

Experience has shown that few anti-tank mines which will be encountered will be capable of exerting an upward energy of more than 60,000 foot-pounds. The exploders shown in Figures 2 to 6 may be designed according to the above equation so as to reduce energy transmitted to the tread and its support to less than one-tenth of this amount. This stress is not greatly in excess of that which is imposed upon the tread structure by the weight of the tank itself as it travels along

over rough terrain. Consequently, by strengthening the bogie wheel as indicated diagrammatically in the drawing and by strengthening the tread pins and side connecting links the tread structure may readily be adapted to this use without extensive changes. As indicated above, it may be desirable to increase the thickness of the steel used in the bottom of the tank body so as to reduce the concussion when a mine is exploded underneath it.

The exploder feet are effective in exerting sufficient pressure over any buried mine, whether the terrain be muddy, rocky or smooth to explode same. By causing a plurality of tanks to travel along in echelon an area can be covered effectively so as to clear it of buried mines. The arrangement is effective even in the presence of barbed wire entanglements which may be erected around the mine field or the use of booby traps or other impeding implements which may be used. The arrangement is particularly effective and offers a decided improvement over prior art equipment providing against the use of remote control mines, that is mines which are detonated through the use of wires attached to the mine trigger and then set some distance away. Remote controlled mines of this character afford a serious menace to devices heretofore designed for mine field clearing since it is possible for the mine clearer to pass over the mine without exploding it and to go some distance ahead before setting off the mine by the trigger wire or otherwise. Thus the body of the vehicle or tank pushing or propelling the clearing device over the mine field may be immediately over the mine when the explosion occurs; and the tank or vehicle, not being built to be self-protective against such explosion, will be disabled or destroyed with its occupants.

As indicated in Figure 1, the projections 18, 18' and 19 will exert pressure over the surface of the ground as the tank passes along and whenever these projections pass over a mine such as that designated 24 in Figure 1, the mine will be exploded and the exploding force will be largely dissipated as internal stress of the heavy mass of the exploder. The remaining portion of the controllable energy from the exploding mine is transmitted through the tread plates 15 to the bogie wheel 12 and a still further reduced amount to the other parts of the conveying means.

Although in this description emphasis is placed upon the use of a tank as the mine field clearing vehicle, it is obvious that the tread modification may be applied to any type of vehicle. It will be clear from the above description that the tread plate with projections or feet may be replaced in the same manner that a broken tread plate is replaced on any track-laying vehicle. Also, while it is indicated that the exploders are welded to the tread plates, it is obvious that it may be desirable in some instances to form the exploders integral with the tread plates. The material of the exploders should be hard armor plate which is highly resistant to both the destructive action of blasts as well as to the erosive effect of the gases released by the explosions. Any other parts of the tread which are exposed to these effects should, of course, likewise be made of the same material. The design and construction is such, as indicated in Figure 1, that the blast from any mine which may be exploded by the projections be deflected away from the tread plate supports and its major effect 75 exerted upon the projections themselves.

While a specific embodiment of the invention has been shown and been described, it will be understood that various alterations may be made without departure from the spirit of the invention as indicated by the appended claim.

Having thus described the invention, I claim:

Mine field clearing apparatus comprising a track-laying vehicle having an endless tread with tread plates, connecting pins extending laterally of the track from each of said tread plates, and a streamlined mine exploder mass of mine blast resistant material integral with each one of said tread plates, said mine exploder mass including a streamlined base portion provided with shoulders extending laterally of the track and over the respective tread plate connector pins thereby providing shielding means therefor, and a plurality of tapered streamlined mine exploding projections integral with said body portion, each of said projections extending to an exposed outer end of relatively small cross section in a ground-engaging direction substantially at right angles to the plane of said one of said tread plates, said

projections being relatively spaced at a distance insufficient to accommodate an anti-tank land mine therebetween, each of said projections enlarging streamlined from said outer end thereof into said body portion to present the minimum of exposed surface to the blast of an exploding anti-tank land mine.
